WALLET

Herbert S. Chase, New York, N. Y., assignor to Bernard Cahn Co., Inc., New York, N. Y.

Application September 6, 1956, Serial No. 42,905

Term of patent 7 years

(Cl. D87—3)

Fig. 1 is a front elevational view of a wallet showing by new design;

Fig. 2 is a side elevational view thereof;

Fig. 3 is an outer plan view thereof as it appears in opened position; and

Fig. 4 is an inner plan view thereof.

The essential features of my design reside in the portions shown in solid lines on the drawing.

I claim:

The ornamental design for a wallet, substantially as shown and described.
